UNITED STATES PATENT OFFICE.

GEORGE W. KING, OF MARION, OHIO, ASSIGNOR TO THE MARION STEAM SHOVEL COMPANY, OF SAME PLACE.

EXCAVATOR.

SPECIFICATION forming part of Letters Patent No. 683,649, dated October 1, 1901.

Application filed June 19, 1901. Serial No. 65,145. (No model.)

To all whom it may concern:

Be it known that I, GEORGE W. KING, a citizen of the United States, residing at Marion, in the county of Marion and State of Ohio, 5 have invented certain new and useful Improvements in Excavators, of which the following is a specification, reference being had therein to the accompanying drawings.

This invention relates to excavators, and 10 more particularly to that type of excavators known as "steam-shovels," and has for its object to provide an improved construction of the dipper and its handle connections, whereby the structure may be made simpler 15 and stronger and at the same time more durable and less subject to wear.

To these ends my invention consists in certain novel features which I will now proceed to describe and will then particularly point 20 out in the claims.

In the accompanying drawings, Figure 1 is a side elevation of a portion of an excavator embodying my invention. Fig. 2 is a front elevation of the dipper. Fig. 3 is a bottom 25 plan view of the same. Fig. 4 is a side elevation of the dipper and its handle connections. Fig. 5 is a plan view of the same. Fig. 6 is a front elevation of the knuckle or connecting piece between the dipper and handle. Fig. 7 30 is a side elevation of the same. Fig. 8 is a plan view of the same. Fig. 9 is an elevation of the back of the dipper. Fig. 10 is a sectional view of the same, taken on the line xx of Fig. 9 and looking in the direction of the 35 arrows; and Fig. 11 is a detail sectional view through one of the dipper-lugs and the adjacent portion of the dipper.

In the said drawings I have shown in Fig. 1 a portion of an apparatus in connection with 40 which my improvements may be employed, the same consisting of a car or body 1, having a boom 2, to which is connected the dipper-handle 3, which carries the dipper 4. It is to the construction of these two last-mentioned 45 parts that my present invention more particularly relates, and it will be understood that those features constituting my present invention may be employed in connection with other apparatus of a similar character.

Referring now more particularly to the construction of the dipper proper, the same con-

sists of a sheet-metal body portion 5 bent into **U** form to constitute the front and sides of the dipper and secured at its rear edges to a back 6 of cast metal, which will be hereinafter more particularly referred to. This body is provided at its inner upper edge with a nosepiece 7, extending around the front of the body at the top and some distance back along the sides thereof, as is usual in structures of this character. The body is also provided with teeth 8, extending above the nosepiece and downward toward the bottom of the dipper, being secured in position by rivets 9. In connection with this nosepiece I 65 employ a protecting sheet or shield 10, preferably of a thickness equal to that of the body of the dipper and extending above the same along the front and the forward part of the sides of the nosepiece 7. The teeth 8 are 70 slotted, as indicated at 11, to embrace the nosepiece and protecting sheet, and said sheet is notched, as indicated in dotted lines at 12 in Fig. 2, so as to extend up along the sides of the teeth above the slot thereof. This 75 construction serves to protect the nosepiece from wear and provide a separate wearing-piece, which may be removed and renewed without requiring the renewal of the entire nosepiece or any other portion of the dipper. 80 The notched construction also serves the purpose of resisting any lateral strain on the teeth, preventing them from being pushed sidewise and taking the strain off the rivets, 85 by which the teeth are secured to the dipper, thus preventing their being sheared off.

The dipper is provided with the usual strengthening-bands 13 and 14 at the top and bottom on the outside thereof, and the front of the dipper is provided with protecting-bars 8^a, preferably of a length and width equal to those portions of the teeth 8 opposite which they lie and of a thickness about equal to the bottom band against which they abut, being secured by the same rivets 9 95 which secure the teeth to the body of the dipper. These protecting bars or strips are found to be quite effective in preventing wear on the front part of the sheet forming the body of the dipper.

The back 6, hereinbefore referred to, is 100 made of cast metal in the form of a plate hav-

ing thereon integral lugs which serve to receive the dipper-braces, the hinge connections for the dipper-handle, and the hinge connections for the dipper-door. The lugs 5 at the top of the back serve to receive the dipper-braces, and the lugs 16 at the bottom of the back serve to receive the handle connection, while the intermediate lugs 17 receive the dipper-door hinges. The back is 10 provided with strengthening-ribs 18 and with forwardly and rearwardly extending flanges 19, by means of which the dipper-body 5 may be the more effectually riveted to the back. By this construction a strong dipper is obtained at a comparatively small expense. The dipper-handle (indicated generally by the reference-numeral 3) comprises a body portion composed of bars 20, between which is located a knuckle-piece 21 in the form of a 15 casting. (Shown more particularly in Figs. 6, 7, and 8 of the drawings.) This knuckle-piece is shaped to receive the bars 20 and is provided with lugs 22, which in conjunction with the lugs 16 on the dipper-back, between 20 which they fit, serve to receive a pivot or pin 23, which effects the connection of the dipper to its handle. It will be thus observed that the casting 21 serves not only as a connecting means between the dipper-handle and 25 dipper, but also as a spacing device to separate or keep apart the members or bars of which the dipper-handle is composed.

The dipper-braces, which are indicated at 24, are connected at their forward ends to the 30 lugs 15 on the dipper-back, while their rear ends are connected to a projection 25 on the dipper-handle. This projection is preferably formed on a casting 26, secured to the knuckle-piece 21, and is provided with a plurality of apertures 27, so as to permit the connection of the braces 24 to said projection by means of a pin or pins 28, inserted through an aperture in each brace and through one of the apertures 27 in the projection. Heretofore it has been customary to carry the 35 braces down to the sides of the dipper-handle and secure them there by pins, provision for adjustment being made by providing a plurality of apertures in the braces. My improved construction above described is 40 advantageous over this former construction, because in the first place it brings the connection higher up and farther from the hinge connection between the dipper and handle, 45 and thereby affords a more efficient brace. In the second place, where the adjusting-apertures are formed in the braces they must of necessity be a considerable distance apart in order to not unduly weaken the braces and 50 are arranged in a single line, whereas in the construction above described the adjusting-apertures may be formed in the projection in two or more rows, so as to permit a much finer adjustment of the dipper relatively to 55 the handle without in any way weakening the connection of the parts.

The dipper-door, which is indicated at 29,

is provided on its under side with the usual hinge-bars 30, which extend upward at the rear in a curve, as indicated at 31, and are 60 pivoted to the lugs 17 on the dipper-back. The forward portions of these bars are riveted to the dipper-door, as indicated at 32; but their rear portions are secured to said door by straps or stirrups 33, riveted to the door and 65 provided with loops through which the hinge-bars pass. This construction is advantageous, for the reason that the strain at this point is particularly severe, and it has not been practicable to insert a sufficient number of 70 rivets through the hinge-bars at these points without unduly weakening said bars. By my improved construction I am enabled to more firmly connect the bars to the door near the rear edge thereof, employing a larger number of 75 rivets than in the usual mode of construction without in any way weakening the bars.

I further provide for strengthening the door by means of braces 34, extending across the 80 under side of the bottom between the hinge-bars 30 and having their ends flanged, as indicated at 35, to fit against the sides of the hinge-bars, so that said braces may be riveted both to the bottom and to the hinge-bars, thus 85 materially strengthening the entire bottom structure. I also provide an improved mode of adjusting the throw of the dipper-latch. This latch is shown at 36 sliding in keepers 37, secured to the cross-braces 34 and pivoted 90 at its rear end to an operating-lever 38, the fulcrum of which is represented by the pin 39. This pin passes through the eye 40 of an eyebolt 41, said eyebolt being threaded to fit a correspondingly-threaded lug 42 on the under side of the dipper-bottom and to receive a locking-nut 43 at the back of said lug. In Letters Patent No. 549,726, granted to me November 12, 1895, I have shown a somewhat similar construction in which the eyebolt carrying the fulcrum of the latch-lever passes through an unthreaded aperture in a lug on the dipper-bottom and is provided with locking-nuts on both sides thereof. I have found by experience that with such a construction 105 grit may enter the aperture in the lug and wear away the thread of the fulcrum-bolt, thus destroying its efficiency, while at the same time the bolt is free to turn sufficiently to permit a loosening of the locking-nuts, thus 110 destroying the adjustment. With the construction which I have now devised and which 115 I have just described no such wearing of the thread is possible, since the aperture in the lug is threaded to receive the bolt, and, moreover, the loosening of the bolt after adjustment is prevented. When it is desired to adjust the latch, the pin 39 is disconnected and the bolt may be given a half-turn or more in either direction and secured after adjustment 120 by the nut 43.

In order to prevent injury to the door and its connections when the door-latch is drawn to permit the door to fall and discharge the

load of the dipper, I provide on the outer end of the dipper-handle a spring-buffer, against which the door may strike instead of striking against the body of the handle. 5 This preferably consists of a frame 44, sliding in a socket 45 in the knuckle-casting 21 and provided with a spring 46, which forces it normally downward and outward in the path of the dipper-door. The spring is held 10 in place by a bolt 47. It will be seen that in case the door falls with sufficient violence to throw it upward against the dipper-handle the spring-buffer above described will receive the shock of the blow and not only prevent 15 injury to the door and handle, but also materially reduce the strain on the dipper-hinges and prevent their being broken.

In Letters Patent No. 589,565, granted to me September 7, 1897, I have set forth a 20 mode of connection between the dipper lugs or trunnions and the body of the dipper, wherein the rivets securing said lugs pass downward through the body of the lug. I have found by experience that this not only 25 weakens the body of the lug, but also limits the number of rivets to be used, so as to affect the strength of the connection. In my present construction (shown more particularly in Fig. 11 of the drawings) I provide in 30 the part of the dipper to which the lugs are connected a recess 48, and each lug or trunnion (indicated at 49) is provided with a flange 50 at its base, fitting within the corresponding recess. The rivets 51, by which the lug 35 is connected to the dipper-body, pass not through the body of the lug, but through the flange 50 and through the body of the dipper, and by reason of this construction I am enabled to employ a greater number of rivets 40 and also rivets of less length, thus obtaining a stronger connection of the parts.

I do not wish to be understood as limiting myself to the precise details of construction hereinbefore described and shown in the accompanying drawings, as it is obvious that 45 these details may be varied without departing from the principle of my invention.

Having thus fully described my invention, what I claim as new, and desire to secure by 50 Letters Patent, is—

1. In an excavator, a dipper provided with a body portion and a nosepiece, in combination with a separate protecting sheet or shield forming an extension of the body and covering 55 the outer portion of the nosepiece, substantially as described.

2. In an excavator, a dipper provided with a body portion, a nosepiece and teeth, in combination with a protecting sheet or shield 60 forming an extension of the body and covering the outer part of the nosepiece and notched at its edge to engage with the teeth, substantially as described.

3. In an excavator, a dipper comprising a 65 body the front and sides whereof are formed of sheet metal, and a back of cast metal, substantially as described.

4. In an excavator, a dipper the body whereof comprises front and side portions of sheet metal, and a back of cast metal provided with 70 strengthening-ribs and with flanges for connection with the sheet-metal sides, substantially as described.

5. In an excavator, a dipper having a body portion the sides and front whereof are formed of sheet metal, and a cast-metal back secured to the sheet-metal sides and provided with integral lugs for the attachment of the dipper connections, substantially as described. 75

6. In an excavator, a dipper having a body 80 portion the front and sides whereof are of sheet metal, and a cast-metal back provided with integral lugs for the handle, brace and door-hinge connections, substantially as described. 85

7. In an excavator, a dipper provided with a door having a body portion, hinge-bars riveted thereto, and straps riveted to the door near the rear edge thereof and forming loops embracing the hinge-bars, substantially as 90 described.

8. In an excavator, a dipper having a door, hinge-bars secured to said door and extending lengthwise thereof, and transverse brace-bars also secured to the door and having 95 flanged ends secured to the hinge-bars, substantially as described.

9. In an excavator, a dipper provided with a door having a latch and an operating-lever, a projection on the door having a threaded 100 aperture, an eyebolt threaded to fit said aperture and forming the fulcrum of the operating-lever, and a lock-nut mounted on said eyebolt, substantially as described.

10. In an excavator, the combination, with 105 a dipper, of a dipper-handle having a body composed of bars, and a terminal casting interposed between said bars which are secured thereto, said casting having lugs to which the dipper is hinged, substantially as described. 110

11. In an excavator, the combination, with 115 a dipper, of a dipper-handle to which the dipper is hinged, said handle being provided with a projection having a plurality of apertures, and a dipper-brace pivotally connected to the dipper and adjustably connected to said projection, substantially as described.

12. In an excavator, the combination, with 120 a dipper, of a dipper-handle provided with a knuckle-casting to which the dipper is hinged, a projection carried by said casting provided with a plurality of apertures located in two or more rows, and a dipper-brace pivotally connected to the dipper at one end and having 125 its other end adjustably connected to said projection, substantially as described.

13. In an excavator, the combination, with 130 a dipper having a hinged door arranged to fall by gravity, of a dipper-handle with which said dipper is connected, said handle being provided with a spring-buffer to receive the contact of the dipper-door, substantially as described.

14. In an excavator, the combination, with a dipper provided with a hinged door arranged to drop by gravity, of a dipper-handle provided with a knuckle-casting to which 5 said dipper is hinged, said knuckle being provided with a socket or recess, a buffer-frame sliding in said socket or recess, and a spring and retaining-bolt for said buffer-frame, substantially as described.
- 10 15. In an excavator, the combination, with a sheet-metal dipper-body the front whereof is provided with teeth at its top and with a bottom band below, of protecting bars or strips extending along said front between the 15 teeth and bottom band on the outside of the body of the dipper, substantially as described.
16. In an excavator, a dipper provided with a sheet-metal body portion having an exter-
- nal bottom band at the front and at the top, projecting teeth extending downward toward 20 the bottom of the dipper on the inside, and protecting-bars having a width equal to the teeth and a thickness equal to the bottom band and extending along the front of the dipper from the projecting portion of the 25 teeth downward to the bottom band, and rivets securing both teeth and protecting bars or strips to the body of the dipper, substantially as described.

In testimony whereof I affix my signature 30 in presence of two witnesses.

GEORGE W. KING.
